R. E. REED.
COBBLER'S OR SHOEMAKER'S KNIFE.
APPLICATION FILED FEB. 8, 1919.

1,309,746.

Patented July 15, 1919.

UNITED STATES PATENT OFFICE.

ROBERT E. REED, OF MORRILL, NEBRASKA.

COBBLER'S OR SHOEMAKER'S KNIFE.

1,309,746.

Specification of Letters Patent. Patented July 15, 1919.

Application filed February 8, 1919. Serial No. 275,761.

To all whom it may concern:

Be it known that I, ROBERT E. REED, a citizen of the United States, residing at Morrill, in the county of Scotts Bluff and State 5 of Nebraska, have invented certain new and useful Improvements in Cobblers' or Shoemakers' Knives, of which the following is a specification, reference being had to the accompanying drawings.

10 This invention relates to an improved cobbler's or shoemaker's knife.

The invention aims to provide a very simple, efficient, and practical device of this kind, which may be manufactured for a 15 small cost, and sold at a reasonable profit.

The invention further aims to provide a trimming knife for trimming the edges of the sole of a shoe, either by imparting a pulling or a pushing action upon the knife.

20 The invention further aims to provide a trimming knife, so constructed and employed, as to avoid cutting the upper of the shoe, while trimming the sole.

The invention further aims to provide a 25 device, in which the blade is sharpened on both of its edges, thereby affording a double-fold purpose for the blade. For instance by this construction the knife may be either pushed or pulled, when trimming the sole 30 of a shoe, thereby permitting the device to be used by the right or the left hand of the cobbler.

Further, since the blade is interchangeable, rather reversible, one of the cutting 35 edges not so constantly used by a right-hand workman, may be employed. Should the workman be left-handed, the cutting edge not so constantly used, may also be utilized, by reversing the blade.

40 It is a further aim of the invention to provide a handle, to which the cutting blade is so connected, that when the blade is in use, in the act of trimming a sole of a shoe, one side of the handle near the blade will engage 45 the bottom face of the sole, and guide the blade, and thereby prevent the upper of the shoe from being cut unnecessarily.

It is obvious that by means of the particular construction shown and described either 50 one of the cutting edges of the blade may be employed for trimming one edge of the welt of the shoe, that is, to bevel the welt slightly, in order to give a finished appearance to the cobbler's work.

55 Further, the end edge of the blade is also sharpened, and it is obvious that either one

of the corners, at the points, where the angularly disposed cutting edges and the end cutting edge adjoin, may be utilized for cutting a stitch receiving channel in the under- 60 face of the sole of the shoe, it being obvious that the handle can be so disposed with relation to and engaging the sole as illustrated, as to limit the depth of the cutting corner of the blade into the sole face. 65

In using a knife of this character, it is possible to easily manipulate the shoe, and thereby facilitate the trimming of the sole.

The present design of this invention is deemed preferable. However, it is obvious 70 that in reducing the device to a practicable form for commercial purposes, alterations in the minor details of construction may be found necessary. The right to these alterations is claimed, provided the alterations fall within the scope of what is claimed. 75

The invention comprises further features and combination of parts, hereinafter set forth, shown in the drawings and claimed.

In the drawings: 80

Figure 1 is a view in perspective showing the sole portion of a shoe, and the cobbler's knife disposed with relation thereto, for trimming the edge of the sole.

Fig. 2 is a perspective view showing the 85 knife employed for beveling the welt of the shoe.

Fig. 3 is a perspective view showing the knife employed for cutting the stitch receiving channel in the under face of the sole of 90 the shoe.

Fig. 4 is a sectional view on line 4—4 of Fig. 2.

Fig. 5 is a sectional view on line 5—5 of Fig. 2. 95

Fig. 6 is a sectional view on line 6—6 of Fig. 2.

Referring to the drawings 1 designates a handle member, which may be any suitable shape or configuration found most convenient for the device, preferably the handle member comprises a hand gripping portion 2 provided with an elongated opening 3 therein in order to lighten the member, and a part 3, which extends at an obtuse angle 100 to the hand gripping portion. The part 3 terminates in an extension 4, the extremity of which is curved or rounded off, as shown at 5. This reduced extension is provided with suitable apertures 6. One edge of the 105 extension is constructed with an elongated recess 8, for the reception of a cutting blade 110

9. This blade may be constructed of any suitable metal, preferably suitably tempered steel, and is provided with a pair of apertures 11. These apertures 11 receive suitable securing screws 12, which are threaded into the openings or apertures of the extension, thereby securely holding the blade to the extension. It is obvious that by the removal of the screws, the blade may easily be reversed, whereby the knife may be used by a right or left-handed workman. The blade may be any suitable shape or configuration, preferably such as shown, and said blade comprises a body part 13, which is received in the elongated recesses of the extension. The blade is constructed very thin, and the cutting part of the blade extends laterally of the extension. The lateral part is of such shape that it is supplied with a pair of cutting edges 14 and 15, extending at acute angles to each other, and the end portion of the blade has an additional cutting edge 16. This cutting edge 16 is at obtuse angles to the former cutting edges, thereby affording sharp cutting gouge corners 17 and 18. Either one of these cutting corners may be employed for cutting a stitch receiving channel in the underface of the sole of the shoe, and since the lateral part of the blade is curved on the face 19, this face may be em-

ployed for flattening the lifted wall 20 of the stitch receiving channel, thereby covering the stitches. The curved end of the extension may also be used for this purpose.

The invention having been set forth, what is claimed as new is:

The combination with a handle member provided with an extension, one edge thereof having a recess, of a thin cutting blade detachably mounted in said recess, said blade 40 having a laterally protruding portion provided with opposite cutting edges at acute angles, the extension adapted to coöperate with one face of the sole, thereby guiding the blade when trimming the edge of the 45 sole, the lateral portion of the blade having an end cutting edge at obtuse angles to the first edges, thereby forming channel cutting gouge corners, the blade and the handle member being so disposed with relation to 50 the sole of the shoe for guiding the instrument, whereby either one of the gouging corners may be adapted to form a stitch receiving channel.

In testimony whereof I hereunto affix my 55 signature in the presence of two witnesses.

ROBERT E. REED.
